LIFTER FOR UTENSILS AND THE LIKE

John L. Thomas, Portland, Oreg.

Application August 26, 1950, Serial No. 181,609

5 Claims. (Cl. 294—30)

1

This invention relates to improvements in lifters for lifting hot pans, bowls, dishes and the like.

A principal object of the invention is to provide as a kitchen utensil a device of the class described so constructed that it can be utilized to pick up and carry hot articles with safety. Another object is to provide such a utensil capable of applying a strong grip, which is convenient to use, made from a minimum number of parts, and economical to manufacture. Another object is to provide a device so constructed that equal torque can be applied to each of the arms forming the gripping jaws. Still another object is to provide a device having rubber covered gripping jaws in order to firmly grip containers having smooth walls, such as glass jars and the like.

The lifter of the present invention comprises a main handle to which is fixedly secured both ends of a U-shaped steel rod, steel strap or other metal bar or strap which forms one jaw. A second jaw is formed by a similar U-shaped rod or strap welded to a longitudinal rod which extends parallel to the handle and which is rotatably mounted in eye bolts adjacent the rear of the handle and in eyes in the rod which forms the first jaw. The rod extending parallel to the main handle is provided with a reverse bend to form an auxiliary handle or grip part offset from the main handle. Movement of the jaws toward and away from each other is effected by rotating the auxiliary handle about the main handle. Movement of the auxiliary handle through an arc of about 90° swings the jaws from fully open to fully closed positions, and vice versa.

The present invention is designed not only for the usual purpose of picking up hot, shallow objects such as lids and plates, but also to pick up deep containers such as fruit jars and the like, and for this purpose the arms of the jaws are arcuately shaped so that a firm grip can be applied by each arm of the jaws to deep containers. Moreover, such construction will grip containers without a flange on the upper edge, by reason of the fact that the arcuately shaped arms extend over the upper edge of such containers and grip the wall of the container at a point well below the rim. Equal gripping pressure can be applied to opposite sides of the container being lifted, by reason of the fact that one of the jaws is secured to and actuated by the rotating rod, while the other jaw is fixedly secured to the main handle and thereby opposes the force applied to the rotating rod with an equal reaction force.

The invention will be better understood and additional objects and advantages will become ap-

2

parent from the following description in connection with the accompanying drawings illustrating a preferred embodiment of the invention. It is to be understood, however, that the invention may take other forms, and all such modifications as will be obvious to persons skilled in the art are included in the invention.

In the drawings:

Figure 1 is a perspective view of the lifter showing the jaws open and gripping a smooth-walled container;

Figure 2 is an end view of the lifter shown in Figure 1 showing the jaws applied to a point adjacent the bottom of the container;

Figure 3 is a side view of the lifter in vertical position and applied to a fruit jar;

Figure 4 shows a modified form of attaching one of the jaws to the longitudinal rod operated by the auxiliary handle;

Figure 5 is a fragmentary view showing one of the jaws covered with rubber; and

Figure 6 is a sectional view taken on the line 6—6 of Figure 5.

The lifter may be made entirely from metal, or it may be made partly of metal and partly of wood, a preferred construction being to construct the main handle from a piece of hardwood and to construct the jaws and rotating handle from metal rod or strap. Such construction provides a lightweight yet sturdy device which will firmly grip pans, bowls or other containers, and will pick up containers of considerable weight.

The lifter is best seen in Figure 1 and is shown gripping the walls of a container A shown in broken lines. The lifter essentially comprises an elongated main handle 10, a pair of U-shaped jaws 11 and 12, and an elongated rod 13, substantially coextensive with handle 10 and rotatably mounted in association therewith. The rod 13 has an auxiliary handle portion 13a in the form of a crank at the rear end thereof.

The jaw 11 is formed from a piece of metal rod or strap, or the like, and comprises arms 11a and 11b and an arcuate cross bar or gripping portion 11c intermediate the arms and at the base of the U. The free ends of the arms 11a and 11b are looped to form eyes 11d and 11e adjacent the ends, and then terminate in bores in the handle 10, as seen in dotted lines in Figure 1. The free ends of the arms are fixedly secured in the handle 10 as by flattening the tips in the form of a rivet, or in any other satisfactory manner. It is essential that these ends be securely attached so that the jaw 11 will function as an integral part of the handle, because a firm grip is necessary to

pick up heavy containers, and especially a container such as exemplified by container A shown in Figure 1 which does not have a flange around the upper edge.

The jaw 12, similar to jaw 11, has arms 12a and 12b and an arcuate, intermediate gripping portion 12c. The free ends of the jaw 12 are welded to the elongated rod 13 which is rotatively mounted in the eyes 11d and 11e and also in eye bolts 17 and 18 at the rear of the handle. The jaw 12 thus rotates with the rod 13 and auxiliary handle 13a in opposition to jaw 11 to grip a pan or the like therebetween. It is an important feature of this invention that each of the arms 11a and 11b and the arms 12a and 12b are fixedly secured to the main handle 10 and rod 13, respectively. Because of this arrangement, these arms each will apply an equal amount of force to the container being gripped. It will be seen that by means of this construction the gripping force is positively applied to both jaws by the use of the two longitudinal members which carry and support the jaws. Equalized pressure permits containers to be handled with safety.

The modification in Figure 4 shows an alternative method, in lieu of welding, of attaching jaw 12 to rod 13. To accomplish this the rod 13 has a flattened portion 13b. The ends of arms 12a and 12b are formed in flat loops which engage the flattened portion 13b with a rigid, driving connection. Equalized pressure by both arms is provided on a container being gripped, as explained herein in connection with the embodiment of Figures 1 and 2.

The auxiliary handle 13a is offset from the main handle 10 by substantially right-angle bends in rod 13 between the eye bolts 17 and 18, and the jaw 12 is rotated by gripping the handle 13a and rotating it relative to the main handle 10. The handle portion 13a has a sleeve 19 loosely mounted thereon for the comfort of the user when the handle is being rotated and gripped. In gripping the device with the right hand, the main handle rests in the palm of the hand, and the sleeve 19 rests in the fingers, thus insuring a strong grip. Articles to be gripped are usually tapered similarly to the container A of Figures 1 and 2 and often are not gripped with a rim or flange. It will be seen that a substantially firm grip would be required to lift the container A because the jaws do not engage a flange around the container, and such a grip is possible with the construction of this device. The lifter will grasp and lift most types of kitchen utensils safely and conveniently.

The arms of the jaws are curved arcuately, as best seen in Figure 2. This construction provides maximum spread of the jaws high up on the arms and thereby facilitates gripping a container sufficiently beneath the top edge so that there is no danger of the jaws slipping off the top edge of the container.

Figure 3 shows the device applied in a somewhat different manner in that the main handle is in a vertical position, and the arcuate shape of the arms is utilized to grip the jar B, with the upper arms 11b and 12b engaging flange 20 of the jar.

The arcuate gripping portions 11c and 12c may advantageously be made of flattened cross-section, as illustrated in Figures 1, 2 and 3. Then, when lifting shallow containers such as plates, lids, or the like, the flat portions 11c and 12c of the jaws are slipped edgewise under the bottom

of the container and the container then conveniently picked up.

Figures 5 and 6 show a modification of the invention. To insure a safe grip on a container and also to prevent damage to containers and the like, a friction material 21, such as rubber or an asbestos filled material, is loosely mounted on the arcuate, cross-bar portions of the jaws corresponding to 11c and 12c in Figure 1. In this modification the cross-bar portion is circular in cross section as shown at 23 in Figure 6. The friction resistant material surrounding the gripping portion of the jaw is preferably formed of triangular cross section 24 having flat sides, as illustrated, and, when pressed against the wall of a container to be lifted, rotates about the cross bar to present a flat surface in frictional engagement with said wall. With such a material surrounding the gripping portions of the jaws, a container having vertical walls can conveniently be handled.

In summary, it will be seen that I have provided the maximum advantages and efficiency for a lifter of the class described, using a minimum number of parts. The lifter comprises essentially the two longitudinal members 10 and 13 which provide the handle, support for the jaws, hand grip, and rotative levers for actuating the jaws. The jaws are forcibly driven into and out of engagement with each other by operation of the handles, and grip. Torque force is applied to both arms of both jaws, thereby providing an equalized gripping pressure on the walls of the container. The arms of the jaws are arcuate to provide the greatest lifting efficiency. The gripping portions may be flattened for efficiency in engaging flat bottomed articles. Alternatively, the gripping portions may be provided with a covering of resilient friction material. One of the jaws provides bearing support for one of the longitudinal members.

It will be appreciated that the longitudinal members may take various forms in relative association to each other. In general, the handle 10, which I have referred to herein as the main handle, may be regarded as stationary, and the rod 13, with its handle portion 13a may be regarded as the rotary member. However, this relationship is purely relative, inasmuch as handle 10 may actually be rotated in the grip and rod 13 held stationary. The handle portion 13a may take different forms. A rear portion of handle 10 might be offset, especially were it to be made of metal. Rod 13 might be disposed centrally of a hollow metal handle with suitable notched openings being provided for the radially extending rotating members. The above and the various other modifications described herein are illustrative of the modifications which may be made within the spirit of the invention.

Having now described my invention and in what manner the same may be used, what I claim as new and desire to protect by Letters Patent is:

1. A lifter for utensils and the like comprising a handle, a first U-shaped jaw having eyes formed near the free ends thereof and having its free ends secured in said handle, a rod constituting an auxiliary handle substantially co-extensive with said handle and rotatably mounted in bearings on said handle and in said eyes in said first jaw, said rod having an offset portion parallel with said handle for manipulating the same, and a second U-shaped jaw secured on said rod in opposed position to said first jaw.

2. The invention as defined in claim 1 in which said rotatable rod has a flattened portion extending substantially the distance between the arms of the jaw secured to said main handle and in which the jaw secured to said rotatable rod is fixedly attached by looping its ends over said flattened portion in close engagement therewith.

3. A lifter for utensils and the like comprising a main handle, a pair of opposing jaws formed of metal rod members in a U-shape, one of said jaws having the free ends of its arms looped to provide an eye near each of said free ends and then having the free ends fixedly secured to said main handle in integral relation, a rod rotatably secured to said main handle and passing through the eyes in said first jaw as a part of its mounting, the other of said jaws having the free ends of its arms fixedly secured to said rod, said rod having an offset portion parallel with the rear of said main handle for gripping by the hand of the operator to effect relative movement between said jaws.

4. A lifter for utensils and the like comprising a handle, a first U-shaped jaw having eyes formed near the free ends thereof and having its free ends secured in said handle, a rod substantially coextensive with said handle and rotatably mounted in bearings on said handle and

in said eyes in said first U-shaped jaw, said rod having an offset portion constituting an auxiliary handle for manipulating the same, and a second U-shaped jaw integrally mounted on said rod in opposed position to said first U-shaped jaw.

5. A lifter for utensils and the like comprising a handle, a first U-shaped jaw having eyes formed near the free ends thereof and having its free ends secured in said handle, a rod substantially coextensive with said handle and rotatably mounted in bearings on said handle and in said eyes in said first U-shaped jaw, said rod having an offset portion constituting an auxiliary handle for manipulating the same, a second U-shaped jaw integrally mounted on said rod in opposed position to said first U-shaped jaw, and friction material covering said U-shaped jaws.
